CLAIM

The ornamental design for a pillar speaker, as shown and described.

DESCRIPTION

FIG. 1 is a side perspective view of a pillar speaker, embodying our new design;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof; and,

FIG. 7 is a bottom plan view thereof.

The broken lines shown are included for the purpose of illustrating the unclaimed portions of the pillar speaker and form no part of the claim.
